UNITED STATES PATENT OFFICE.

LUTHER R. FAUGHT, OF PHILADELPHIA, PENNSYLVANIA.

CHILL FOR CASTING CAR-WHEELS.

SPECIFICATION forming part of Letters Patent No. 341,326, dated May 4, 1886.

Application filed February 10, 1886. Serial No. 191,415. (No model.)

To all whom it may concern:

Be it known that I, LUTHER R. FAUGHT, of the city and county of Philadelphia, in the State of Pennsylvania, have invented a certain 5 new and useful Improvement in Chills for Car-Wheels, of which improvement the following is a specification.

My invention relates to chills for casting car-wheels of that class or type in which a 10 circular series of segmental blocks is employed to receive and form the outer boundary of the molten metal of which the casting is composed; and the object of the invention is to insure the utilization of the inward expansion of the seg- 15 ments of the chill to as high a degree as practicable in maintaining their close and continuous contact with the metal of the casting, thereby attaining a correspondingly complete and uniform density of chill upon the tread of 20 the wheel and regular circular contour of the same.

To this end my invention, generally stated, consists in the combination of a continuous rim or outer section, an inner section 25 which is radially divided into a series of separate chilling blocks or segments, each connected with the outer section, and a circumferential series of ties or connecting-pieces by which the segments of the divided inner sec- 30 tion are united one to another.

The improvement claimed is hereinafter more fully set forth.

In the accompanying drawings, Figure 1 is a plan or top view of a chill embodying my 35 invention; Fig. 2, a vertical section through the same at the line *x x* of Fig. 1; and Fig. 3 a view in elevation of a portion of the same, as seen from the bottom.

In the practice of my invention I construct 40 a chill having a continuous circular outer section or rim, 1, the depth of which may be about equal to or somewhat greater than the width of the treads of the wheels for the casting of which the chill is designed, and an inner section composed of a circular series of chilling blocks or segments, 2, which are arranged closely adjacent one to the other, the inner diameter of the ring formed by the series of blocks corresponding substantially with that 45 of the treads of the wheels to be cast. The inner surfaces of the blocks or segments 2 correspond in vertical outline and depth with the

wearing-surface of the tread and inner side of its flange, and each segment is connected by a radial arm or plate, 3, with the outer section, 55 1. The segments 2 and arms 3 are preferably cast integral with the outer section, 1, the segments 2 being separated one from the other by narrow radial splits or divisions 4, which may be formed either by the insertion of suitable 60 dividing-pieces in the mold in casting the chill or by sawing out subsequently thereto.

It will be obvious that, if preferred, any desired number of the segments may be cast together in separate groups and bolted or riveted 65 to an outer section.

Under the above-described construction the action of the high temperature of the molten metal poured into the chill in casting a wheel induces an inward expansion of the segments 7c 2 and arms 3, which tends to hold the segments against the outer surface of the metal during and after its solidification, and, by the contact of the comparatively cold surfaces of the segments with the metal, to effect such abstraction 75 of heat therefrom as is requisite to form a chill of proper density and depth on the tread and flange. It will be seen that the effectiveness of such inward expansion of the segments and the radial arms by which they are connected 80 to the continuous outer section will be increased proportionately to the increase of length of the arms; but an increase of length of the arms to the extent which is desirable involves the objection that the segments are weak and defi- 85 cient in lateral support, and hence the true circular form of the chill cannot be readily produced by turning, nor can it be maintained with certainty during the changes of temperature which occur between the pouring and the 90 solidification of the metal. To obviate such objection I provide a system of circumferential bracing for the chilling blocks or segments, which affords what may be termed a "semi- 95 divided inner section" in the chill—that is to say, one whose members are connected at their opposite ends alternately in such manner that while ample scope is admitted of for their independent inward expansion, they are continuously braced and supported as against 100 the tendency of the section to be distorted either from its normal internal circular figure or from true vertical lateral alignment. To this end the segments 2 are united one to the other

alternately at or near their upper and their lower ends by a circumferential series of ties or connecting-pieces, 5 6, extending across the spaces between the arms 3, and cast integral 5 with the other members of the section or group of members of the section, as the case may be. The ties 5 6 are located as closely as may be to the outer surfaces of the segments 2—that is, at or near the inner ends of the 10 radial arms 3—and each segment is connected to the adjacent segment on one side by an upper tie, 5, and to that on the opposite side by a lower tie, 6. The same principle of connection of the segments may be utilized without 15 the provision of special ties bridging the spaces between the arms, as shown, by discontinuing the divisions 4 between the segments alternately at and near their upper and their lower ends. A continuous lateral support is thus 20 afforded to the entire series of segments forming the inner section, which insures its uniform contraction around the hot metal which it receives, and thereby tends to preserve its circular form and lateral alignment under the 25 inward expansion of the arms and segments throughout the life of the chill, and such expansion is exerted freely and effectively upon the metal by reason of the alternate yielding of the segments at top and bottom uniformly 30 around the section.

I claim as my invention and desire to secure by Letters Patent—

1. The combination, in a chill, of a continuous rim or outer section and an inner section composed of a series of separate chilling blocks 35 or segments, each connected radially to the outer section and circumferentially to an adjacent segment, substantially as set forth.

2. The combination, in a chill, of a continuous rim or outer section and an inner section 40 composed of a series of separate chilling blocks or segments connected radially to the outer section and circumferentially one to another at or near their upper and their lower ends, respectively, substantially as set forth.

3. The combination, in a chill, of a continuous rim or outer section, an internal concentric circular series of chilling blocks or segments separated by radial divisions, a series 45 of radial arms or plates, each extending from one of said segments to the outer section, and a series of circumferential ties or connecting-pieces uniting said segments and radial arms at or near their junction and alternately at or near their upper and their lower ends, re- 55 spectively, substantially as set forth.

LUTHER R. FAUGHT.
